UNITED STATES PATENT OFFICE.

CLAY M. RUNYAN, OF LAKEWOOD, OHIO, ASSIGNOR, BY MESNE ASSIGNMENTS, TO THE ADVANCE MANUFACTURING COMPANY, OF DETROIT, MICHIGAN, A CORPORATION OF MAINE.

FEEDING DEVICE FOR BLANKS.

1,292,377.

Specification of Letters Patent. Patented Jan. 21, 1919.

Application filed November 29, 1912, Serial No. 733,967. Renewed March 30, 1916. Serial No. 87,852.

To all whom it may concern:

Be it known at I, CLAY M. RUNYAN, a citizen of the United States, and resident of Lakewood, in the county of Cuyahoga and 5 State of Ohio, have invented certain new and useful Improvements in Feeding Devices for Blanks, of which I hereby declare the following to be a full, clear, and exact description, such as will enable others 10 skilled in the art to which it appertains to make and use the same.

This invention relates to mechanism for feeding blanks from a pile of blanks to a position for printing.

15 One object of the invention is to provide improved mechanism for feeding cards or other blanks to the printing mechanism of an addressing or other printing machine.

Another object of the invention is to provide 20 a blank feeding feeding mechanism of simple form adapted to feed forwardly successively the blanks from a pile of blanks.

Another object of the invention is to provide, in mechanism of this character, means 25 for relieving the blank feeding member of the weight of the pile when it moves forwardly.

With these and other objects in view, the 30 invention consists of the parts and combination or combinations of parts hereinafter described and set forth in the appended claims.

In the accompanying drawings Figure 1 is a side elevation of a combined printing 35 and addressing machine provided with a blank feeding device embodying my invention; Fig. 2 is a fragmentary section of the receptacle for blanks, and feed rolls showing the feeding mechanism for the blanks;

40 Fig. 3 is a side elevation of the pivoted feed arm, shown in its rearward limit of movement; Fig. 4 is a similar view showing the feed arm in its depressed position; Fig. 5 is a plan view of the receptacle and Fig. 6 is 45 a vertical section of one feeding plate.

In these views A is the bed plate or frame of the machine chosen as one example of printing mechanism to which my invention may be applied. B indicates as an entirety 50 mechanism for supporting and successively moving to and from the printing position slugs C. The feeding or moving mechanism B preferably comprises an endless chain or carrier passing around wheels E, F, the former wheel being fixed to a driven shaft

G, which serves to operate the chain. The slugs C may be placed in a suitable holder or receptacle D from which they are preferably delivered by gravity to the chain B.

The blanks, which may be cards, are 60 stored in a receptacle D which is provided with a rigid bottom I, which is preferably inclined to facilitate the movement of the blanks. J indicates one or more openings formed in the bottom I. The purpose of 65 these openings will be later described. K indicates an inclined rigid rear wall extending part way up the receptacle, and L, L, indicate rigid side walls which retain the cards in place.

The upper portions of the front and rear walls M and N respectively are pivoted at at m and n to move freely backward and forward at their upper ends.

O is a hinged gate or guard at the lower 75 end of the front wall. The gate O is preferably adjustable to regulate the width of the opening in conformity to the thickness of the blanks passing through said opening. o' indicates a set screw which may be provided to hold the gate O in its adjusted position.

P, P are feeding members for the blanks, each movable in and through one of the 80 openings J, J. Each member is provided with an adjustable raised edge or flange p, adapted to engage the rear end of each blank in turn and propel the blank forward. The inclined face of the rear wall serves to stack the blanks in a stepped position, 90 and hence permits the propelling edges of the feeding members P to engage the rear edge of each blank in turn without disturbing those above.

The feeding members P, P are inclined 95 to correspond to the inclination of the bottom I of the receptacle D'.

These feeding members P, P are operated to impart an upward and forward movement to the blanks when feeding them 100 so as to raise them off from the bottom and thereby to eliminate the friction of the bottom on the lower sides of the blanks, and also to agitate them so that they will become loosened from one another and feed 105 one at a time. The rear extremity of the member P is elevated more than the forward end, thus increasing the above mentioned efficiency of the said member.

These members P, P are operated to im-

part a downward and rearward movement thereto on their return so as to pass below the bottom of the receptacle and permit the stack of blanks remaining in the receptacle 5 to drop and rest thereon preparatory to another forward movement of another bottom card.

The means for obtaining this peculiar movement is shown in the figures to be an 10 arm P' pivoted to P^2 to the frame, the pivot opening P^3 being elongated to permit of longitudinal movement.

Upon this pin the arm obtains both a reciprocating and oscillating movement by 15 means of two cams Q and R upon the main shaft G . The arm is provided with a fork S and in this fork the cam Q operates to give the forward and rearward movement to the arm.

20 The second cam R is provided with a flat side r and the arm with a shoulder R' and when the cam R reaches such a position that the shoulder R' will be presented to the flat side of the cam, the outer end of the 25 arm will drop and will permit the feeding members P , P , to pass below the bottom of the receptacle. These positions of the cam and arm are shown in Figs. 2, 3 and 4.

In Fig. 2 the arms and feeding members 30 are shown in the forward position and the blank X is fed between feed rollers X' , X' operated by gears X^3 , X^4 and through a guide X^2 to the printing position for a slug C carried upon the carrier B , as already described. The pressure is obtained 35 by means of the roller Z operatively connected with the main shaft G by means of the gears Z' and Z^2 .

To lessen the weight upon the lower 40 blank, the upper portions of the receptacle walls are inclined forward simultaneously with the upward and forward movement given the blank. This action causes the weight of the upper portion of the stack 45 of blanks to be partially supported upon the front wall and likewise lessens the weight upon the front edge of the blank, which is being propelled forward and thus assists its progress.

50 To further assist this forward movement of the blanks, each plate is provided with fine points T , T which will engage the bottom of the blanks and prevent slipping.

A thin rubber sheet X^4 holds these points 55 and can be cemented to each plate. Carborundum or emery cloth can be substituted for the rubber plate.

The pivoted walls of the receptacle are 60 operatively connected by means of links V , V with upwardly extending arms W , W upon the reciprocating arm P' .

This same principle of mechanism can be 65 utilized in feeding the blank from a column of blanks, when the latter occupy a position in the receptacle at any other angle

differing from the position shown in the accompanying drawings.

To those skilled in the art of making apparatus of the character described, many modifications of and widely differing embodiments and applications of my invention will suggest themselves, without departing 70 from the spirit and scope thereof. My disclosures and the descriptions herein are purely illustrative and are not intended to 75 be in any sense limiting.

Having described the invention what I claim as new and desire to secure by Letters Patent is:

1. In a blank feeding device for a printing machine, a receptacle having a bottom formed with an opening, a feeding member, a pivoted arm on which said feeding member is mounted, said arm having a slot through which the pivot for said pivoted arm passes, an actuating shaft, and cams on said shaft for operating the front end of said arm upwardly and forwardly in one direction, and rearwardly and downwardly 85 in the other direction.

2. In a blank feeding device for a printing machine, a blank receptacle having an inclined lower rear wall, and swinging upper front and rear walls, a bottom for the receptacle having an opening, a blank feeding member operable through said opening and having an upward and forward and downward and rearward movement, and connections between said upper front and rear walls and said feeding member, whereby by said walls move forward at their upper ends coincident with the upward and forward movement of said feeding members.

3. The combination with a receptacle having an inclined lower rear wall and tilting upper front and rear walls, and a bottom having an opening, of a reciprocating feed member operable through said opening, said feed member having an upward and forward, and a downward and rearward movement, means for operating said feed member, and means for tilting said front and rear walls to correspond with the movements of said feed member.

4. In a blank feeding device, the combination of a blank receptacle having front and rear walls, a bottom for the receptacle formed with an opening, a blank feeding member having an extension adapted to project through said opening, said member being formed with an elongated slot, a pivot shaft extending through said slot, and cam means operatively connected with said blank feeding member and adapted to give an upward and forward and downward and rearward movement thereto, the slot in said feeding member permitting rotary and sliding movement thereof upon said shaft.

5. In a device for feeding blanks in a printing machine, a receptacle, a movable

- feeding device having a blank engaging member movable in the bottom of said receptacle, said member adapted to engage each blank in turn, said feeding device having intermediate of its ends a slot through which a pivot pin projects to permit upward, downward and reciprocating movement of said blank engaging member, and cam means engaging said feeding device for 5 moving it on said pivot pin. 6. In a blank feeding device for a printing machine, the combination of a receptacle having swingable front and rear walls and a bottom adapted to hold a plurality of 15 blanks, said bottom being formed with an opening, a device movable in and relative to the opening in said bottom for feeding the lowermost blank forwardly, and means for swinging said front and rear walls in coöperation with the movement of said feeding 20 device. 7. In a blank feeding device for a printing machine, the combination of a receptacle having swingable front and rear walls and a bottom adapted to hold a plurality of 25 blanks, said bottom being formed with an opening, a device movable in and relative to the opening in said bottom for feeding the lowermost blank forwardly, and means for simultaneously swinging said front and rear walls in coöperation with the movement of 30 said feeding device. 8. In a blank feeding device for a printing machine, the combination of a receptacle having a bottom formed with an opening 35 adapted to support a pile of blanks, a device movable in and relative to the opening in said bottom for feeding the lowermost blanks of the pile forwardly, and means for moving the uppermost blanks in the pile 40 relative to the blanks therebelow to relieve said feeding device of the weight of the blanks while said feeding device is operating. 9. In a blank feeding device for a printing 45 machine, the combination of a receptacle having a bottom formed with an opening adapted to support a pile of blanks, a device movable in and relative to the opening in said bottom for feeding the lowermost 50 blanks of the pile forwardly, and means connected with said feeding device for moving the uppermost blanks in the pile relative to the blanks therebelow to relieve said feeding device of the weight of the blanks while 55 said feeding device is operating. 10. In a feeding device for a printing machine, the combination of a receptacle adapted to support a pile of blanks, the front and rear walls of said receptacle being swingable forwardly and rearwardly, a movable 60 device at the lower end of said receptacle for feeding the lowermost blank forwardly, and means for swinging said front and rear walls in coöperation with the movement of said feeding device. 11. In a feeding device for a printing machine, the combination of an inclined receptacle adapted to hold a pile of blanks, the front and rear walls of said receptacle being swingably mounted, a movable device 70 disposed at substantially right angles to the receptacle and arranged to feed forward the lowermost blank of the pile, and means for swinging said front and rear walls forwardly in coöperation with the movement of 75 said feeding device. 12. In a feeding device for a printing machine, the combination of a receptacle adapted to receive a pile of blanks, the front and rear walls of said receptacle having 80 lower stationary parallel sections arranged to hold the blanks in stepped relationship to each other and upper swingable sections, a movable device arranged to feed the lowermost blank forwardly, and means for swinging 85 said upper sections in coöperation with the movement of said feeding device. 13. In a feeding device for a printing machine, the combination of a receptacle adapted to receive a pile of blanks, the front 90 and rear walls of said receptacle having lower stationary parallel sections arranged to hold the blanks in stepped relationship to each other and upper swingable sections, a movable device arranged to feed the lowermost blank forwardly, and means connected 95 with said feeding device for swinging said upper sections in coöperation with the movement thereof. 14. In a feeding device for a printing machine, the combination of a receptacle inclined downwardly and rearwardly and adapted to receive a pile of blanks, the front and rear walls of said receptacle having 100 lower stationary sections disposed at an inclination to the longitudinal axis of said receptacle, whereby a portion of the blanks are arranged in stepped relationship, and upper swingable sections, a movable device 105 for feeding the lowermost blank forwardly, and means for swinging said upper sections in coöperation with the movement of said feeding device. 15. In a feeding device for a printing machine, the combination of a receptacle inclined downwardly and rearwardly and adapted to receive a pile of blanks, the front and rear walls of said receptacle having 110 lower stationary sections disposed at an inclination to the longitudinal axis of said receptacle, whereby a portion of the blanks are arranged in stepped relationship, and upper swingable sections, a movable device 115 for feeding the lowermost blank forwardly, and means for swinging said upper sections in coöperation with the movement of said feeding device. 16. In a feeding device for a printing machine, the combination of a receptacle inclined downwardly and rearwardly and 120

adapted to receive a pile of blanks, the front and rear walls of said receptacle having lower stationary sections disposed at an inclination to the longitudinal axis of said receptacle, whereby a portion of the blanks are arranged in stepped relationship, and upper swingable sections, a movable device for feeding the lowermost blank forwardly, and means connected with said feeding device for swinging said upper sections forwardly and rearwardly.

17. In a feeding device for a printing machine, the combination of a receptacle adapted to hold a pile of blanks, a reciprocating device at the lower end of said receptacle arranged to feed forwardly at the lowermost blank of the pile, a support for said device, and a pair of cams constructed and arranged and operating substantially

simultaneously to swing and bodily slide 20 said feeding device on said support.

18. In a feeding device for a printing machine, the combination of a receptacle adapted to hold a pile of blanks, a reciprocating device at the lower end of said receptacle arranged to feed forwardly the lowermost blank of the pile, means arranged in front of said receptacle for swingably and slidably supporting said feeding device, and a pair of cams for swinging and sliding 30 said feeding device on said supporting means.

In testimony whereof, I hereunto set my hand this 26 day of November, 1912.

CLAY M. RUNYAN.

In presence of—

H. H. ANDERSON,
Wm. M. MONROE.
